REPEATER-TESTING ARRANGEMENT.

1,404,288.

Specification of Letters Patent. Patented Jan. 24, 1922.

Application filed May 16, 1919. Serial No. 297,517.

To all whom it may concern:

Be it known that I, WILLIAM H. HARDEN, residing at Brooklyn, in the county of Kings and State of New York, have invented certain Improvements in Repeater-Testing Arrangements, of which the following is a specification.

This invention relates to transmission circuits and more particularly to a method of 10 and means for testing repeater apparatus associated with such circuits.

It is one of the essential features for the proper operation of repeater circuits well known in the art and suitable for transmission in either direction, that the line in either direction shall be balanced by an artificial line or network, which is designed to have so far as practicable the same impedance and capacity as the line itself. Under 20 conditions existing in actual practice however it is impossible to obtain an absolutely perfect balance between the line and the artificial line or network, and if the degree of unbalance becomes great enough in any 25 particular case there will be sufficient of the output current from one of the repeaters shunting into the input circuit of the other repeater and being repeated thereby back to the first repeater, to start a circulation of 30 energy in the repeater circuit that will set up an action therein known as "singing," which action will prevent the effective transmission of speech over the circuit. Furthermore, considerable distortion of the voice 35 currents may be introduced by a condition of unbalance although the gains are not large enough to cause "singing." The tendency of the repeaters to "sing" or cause distortion because of unbalance in the circuit 40 may be reduced by adjusting the repeaters for lower gains in transmission, or in other words to cause them to operate with a smaller degree of amplification. It is, therefore, evident that one of the primary disadvantages of a condition of unbalance in a 45 repeater circuit is the reduction of the amount of gain, or improvement in transmission, which it is practicable to obtain with the repeater apparatus, the amount of 50 reduction necessary being dependent upon the degree of unbalance.

The general purpose of this invention is to provide a means for detecting a condition of unbalance between a line and artificial line and associated apparatus, which means 55

shall be more accurate and sensitive than former arrangements, and whereby smaller degrees than heretofore of unbalance may be detected and measured.

In former methods of measuring or detecting a condition of unbalance in a repeater circuit the output circuit of one of the repeaters would be disassociated from the opposite line section and would be associated with the same line section as the input circuit of that repeater. The operator's listening or supervising set would now be connected with the line and the gain of the repeater would be increased step by step until the operator could note the occurrence of "singing" in the apparatus. A relationship has been established between the reading on the potentiometer, or other means for increasing the repeater gain, when "singing" is observed and the degree of unbalance between the line and network which served as a means for measuring the latter. Such a method has proved satisfactory in rapidly determining the existence of large unbalances, but has not been sufficiently sensitive to prove useful in detecting small unbalances, such as those usually encountered where office equipment is involved. This is due to the fact that the gain given by one repeater element alone would not be sufficiently large to cause the apparatus to "sing" where relatively small unbalance of such a type was involved. In the improved testing arrangement of this invention both of the repeater elements are connected during the test in tandem. Such an arrangement utilizes the gain from both repeater elements to such an extent as to extend the range of the test to detect and measure unbalances of much smaller magnitude than previously.

Other features of the invention will be clear from the following detailed description of the arrangement.

In the drawing is shown a circuit diagram of a transmission line including repeater apparatus, wherein the arrangements of this invention are embodied. Connected to section L_1 of a transmission line is the input circuit of a vacuum bulb repeater A_2 . In the input circuit is included the potentiometer P_2 whereby the gain of the repeater may be adjusted to different degrees. The output circuit of repeater A_2 is inductively related by the three winding transformer 2 to another section of the transmission line, 110

- such as L_2 . Connected to section L_2 of the line is the input circuit of a vacuum bulb repeater A_1 , in which input circuit is included the potentiometer P_1 , whereby the 5 gain of the repeater A_1 may be adjusted to different degrees. The output circuit of repeater A_1 is inductively related to line L_1 by means of the three winding transformer 1. While the repeater elements A_1 and A_2 10 have been illustrated as of the vacuum bulb type, it is understood that other types of repeaters such as the well known mechanical repeater may be employed. If mechanical repeaters were employed there would be substituted for the potentiometers P_1 and P_2 15 adjustable rheostats for regulating the gains of the repeaters. The jacks J_2 and J_7 associated with the repeater set are commonly termed repeater line jacks and serve as a 20 means whereby the repeater set may be connected to different lines or testing apparatus. The jacks J_3 and J_6 commonly termed repeater network jacks serve as a means for associating with the repeater any 25 desired networks or testing apparatus. The networks N_1 and N_2 are shown associated with the repeater set and are adapted to balance the line sections L_1 and L_2 , respectively. 30 If for purposes of illustration it is desired to test and measure the condition of balance between a line, such as L_1 , and its balancing network, such as N_1 , the repeater set will be disconnected from the line L_2 35 by inserting a short circuit plug (not shown) in repeater line jack J_2 . The network N_2 will be disconnected from the repeater set by inserting an open circuit plug (not shown) in the repeater network jack 40 J_3 . This operation will so arrange the transformer 2 that the left hand line windings thereof will operate substantially as an ordinary repeating coil and thus connect the output circuit of repeater A_2 to the input 45 circuit of repeater A_1 . Accordingly the energy initially transmitted from the line L_1 will be transmitted through the repeater A_2 , through the transformer 2, through the repeater A_1 , and thence to transformer 1. If 50 a perfect condition of balance existed between line L_1 and network N_1 none of this energy would be transmitted from transformer 1 back into the input circuit of repeater A_2 and no continuous circulation 55 of energy would take place in the repeater set. However under actual conditions it is practically impossible to provide this condition of perfect balance between the line and network. Accordingly a portion of the energy 60 will be transmitted from transformer 1 back into the input circuit of repeater A_2 . When the increase of energy caused by the amplifying elements is greater than the loss in the rest of the repeater system the amount 65 of circulating energy increases to a value limited by the characteristics of the repeater elements and associated circuits. This action is known as "singing." The repeater set may be caused to "sing" either by increasing the amplification of the repeater elements or by increasing the unbalance between the line and networks until the "singing point" is arrived at. For the purposes of this test the gain of the amplifiers may now be increased by adjusting the 70 potentiometers P_2 and P_1 until the "singing point" is arrived at. The operator or attendant by connecting a listening or supervising set (not shown) to the repeater apparatus may ascertain when the "singing" 75 point has been arrived at. When the "singing point" has been arrived at the settings on the two potentiometers should be added and the reading noted. This reading, for convenience, may be termed the "singing" 80 point with plus poling.
- The previously mentioned short circuit plug and the open circuit plug should now be interchanged so that the short circuit plug is in the jack J_3 and the open circuit 85 plug is in jack J_2 . It will be seen that this operation will so arrange the transformer 2 that the right hand line windings thereof will operate as a repeating coil and will thus couple the output circuit of repeater A_2 to 90 the input circuit of repeater A_1 . In this case, however, the direction of the input current of repeater A_1 is reversed with respect to its previous condition. In the same manner as previously pointed out the 95 potentiometers P_2 and P_1 should now be adjusted until the "singing point" is arrived at. The settings on the potentiometers should then be added and the reading noted 100 may for convenience be termed the "singing" 105 point with minus poling.
- Of the two readings, such as the "singing point with plus poling" or "the singing point with minus poling," obtained as described it has been found in practice that 110 the lower reading has been the more representative and should in all cases be the reading used for testing purposes. To this reading, which will be in mile units, as the potentiometers are calibrated in such units, 115 there should be added six miles. This is to make the results obtained in this test comparable to the results obtained with the former methods of testing unbalance in which but one of the repeater elements was 120 employed and so that the same standards of comparison between the amount of unbalance and the "singing point" of the repeater may be used in both tests. The explanation for this addition of six miles is 125 as follows: in the ordinary form of repeater circuit the effective gain obtained from the repeater set is less than the actual gain given by one of the bulbs by an amount equal to approximately six miles due to the 130

fact that in both the input and output sides of the repeater circuit the energy is divided into half. The transmission gains for the different potentiometer settings when measured by means of the testing unit are the effective gains as described above. In the case of the testing arrangements of this invention use is made of two bulbs with their associated potentiometers while the energy losses correspond practically only to the loss incurred in former testing arrangements where only one of the bulbs was used. Accordingly in this arrangement the effective gain is then about six miles greater than the calibrated potentiometer settings indicate and six miles should be added to this reading. The results now obtained will be comparable to the results of former tests with one bulb and the relationship between the degree of unbalance between the line and network and the point at which the repeater "sings" as indicated by the potentiometer readings will afford a means of measuring the amount of unbalance.

It sometimes happens that the repeater set will not have repeater network jacks such as jacks J_3 and J_6 associated therewith but will have the networks permanently associated with the repeaters. In such arrangements and in cases where it is not convenient to use patches or plugs in the network jacks a slightly different method of testing for unbalance must be used, which is as follows: if, for purposes of illustration, it is desired to test or measure the condition of balance between the line L_1 and the network N_1 , the repeater will be disconnected from line L_2 by the insertion of a short-circuit plug in the repeater line jack J_2 . This will cause the transformer 2 to function as a repeating coil and will couple the output circuit of repeater A_2 with the input circuit of repeater A_1 . In the same manner as previously pointed out the operator or test man will connect a listening or supervising set with the repeater and will now adjust the potentiometers P_2 and P_1 so as to increase the gain of the repeaters, step by step and alternately, until the "singing point" is arrived at. The settings on both potentiometers will then be added and for convenience may be termed "singing point with plus poling."

The test should then be repeated with an open circuit plug inserted in jack J_2 instead of the short circuit plug. This latter reading may for convenience be termed the "singing point with minus poling." As in the former test the lower of the two readings will be found to be more representative and should be chosen.

During this second form of test it is to be noted that the network of the line not under test, such as network N_2 , is allowed to remain connected to the repeater set. This

causes a loss of approximately six miles in the repeating coil formed by the output transformer 2 and thus practically offsets the six miles difference due to having two bulbs and one transformer as referred to above. It therefore happens that this second form of test gives results which are comparable with those obtained with the earlier type of test with one bulb, and accordingly it is not necessary to add six miles to the potentiometer readings in this case.

For determining the balance conditions between the networks N_2 and line L_2 , the procedure is exactly the same as explained above, except that the repeater line jacks, such as J_7 , and the repeater network jacks, such as J_6 , are opened or short-circuited as noted.

While the arrangements of this invention have been specifically illustrated herein as adapted to test the balance condition of a line and networks with which vacuum bulb repeaters are associated, the testing method herein embodied may be applied equally well, in the case where mechanical repeaters are used. Furthermore while the invention has been disclosed as embodied in certain specific arrangements which have been deemed desirable it is understood that it is capable of embodiment in many and widely varied forms without departing from the spirit of the invention as defined in the appended claims.

What I claim is:

1. In a transmission system including two line sections balanced by artificial lines and interconnected by a two-way two-element repeater, the method of testing the condition of balance between one of said line sections and its artificial line, which consists in impressing energy from the output circuit of the repeater element whose input circuit is associated with the line to be tested on the input of the other repeater element, and in increasing the gain of said repeater elements until "singing" takes place in said repeater set.

2. In a transmission system including two line sections balanced by artificial lines and interconnected by repeaters, said repeaters being associated with transformers and having their input circuits bridged across the midpoints of said transformers and having their output circuits connected to said transformers in such a manner that when a condition of balance exists between said line sections and artificial lines that none of the energy from the output circuit of one of said repeaters will be transmitted through one of said transformers to the input circuit of the other of said repeaters, the method of testing the condition of balance between one of said line sections and its artificial line, which consists in creating a condition of unbalance between the line and network

4
terminals of the transformer associated with the other of said lines so that energy from the output of one of said repeaters will be transmitted to the input of the other repeater, and in increasing the gain of said repeaters until "singing" takes place.

3. In a transmission system two line sections, artificial lines for balancing said line sections, repeater elements for interconnecting said line sections, three winding transformers for associating said repeaters with said line sections, the input circuits of said repeaters being associated with the midpoints of two of said windings of each of said transformers and the output circuits of said repeaters being so related to said windings that when a condition of balance exists between said line sections and artificial lines

substantially none of the energy from the output circuit of one of said repeaters will be transmitted to the input circuit of the other repeater, and means for creating for testing purposes an open and closed circuit between the line and network terminals of the transformer associated with one of said line sections and its artificial line whereby said transformer windings will operate efficiently as a repeating coil and transmit energy from the output circuit of one of said repeaters into the input circuit of the other repeater.

In testimony whereof, I have signed my name to this specification this 15th day of May, 1919.

WILLIAM H. HARDEN.
